UNITED STATES PATENT OFFICE.

WILLIAM BISHOP HUGHES, OF PHILADELPHIA, PENNSYLVANIA.

MACHINE FOR DRILLING AND REAMING.

SPECIFICATION forming part of Letters Patent No. 429,526, dated June 3, 1890.

Application filed December 27, 1889. Serial No. 335,155. (No model.)

To all whom it may concern:

Be it known that I, WILLIAM BISHOP HUGHES, a citizen of the United States, and a resident of the city of Philadelphia, in the 5 State of Pennsylvania, have invented certain new and useful Improvements in Machines for Drilling and Reaming Metal, of which the following is a full and complete specification.

My invention relates to that class of reaming and drilling machines which are employed generally upon bridge-work, where the holes for rivets are generally punched, and in consequence it is impossible to get a line of holes in two or more plates to coincide so accurately when punched that a rivet can be inserted through several holes. It is therefore necessary when several pieces of metal having punched holes are put together to ream the holes with a free moving reamer, 15 so as to make the holes in the various sheets of metal coincident. This requires a very free moving machine and one which will allow the reamer when put into a hole to adjust itself and find the center of several holes for 20 itself, thus making the hole with the least expenditure of time and power. I have shown in the drawings and will hereinafter describe a machine in which this is possible, made so by the peculiar arrangement of the structure 25 30 which gives it all the necessary motions to make an easy and quick working-machine and to apply the reamer or drill by power with all the facility which could be acquired with a hand-tool.

I propose to manipulate my machine by hand, communicating power to it so freely as to enable the operator to move it back and forth, up or down, sidewise, or in a circular direction with one hand and with great ease.

The particular purpose of my machine is 40 to make a rapidly-moving and easily-handled machine, which can be caused to do a wide range of execution upon a piece of stationary work. A bridge-girder or other similar structure 45 may be mounted upon proper supports beneath the machine, and then the machine moved over it to do all work within its reach without moving the work. This has great advantages of economy in speed and labor in 50 the manufacture of bridges.

In the drawings, Figure 1 represents a side

elevation of my reaming and drilling machine with the bracket partially in section. Fig. 2 is a front elevation of the bracket. Fig. 3 is a front elevation of the drill and reamer head 55 with the end of the crane-arm in section, showing the way in which the drill-head is mounted upon the crane-arm. Fig. 4 is a sectional side elevation of the drill-head, showing the way in which it is mounted upon the crane-arm, 60 and its internal structure. Fig. 5 is a horizontal section through yy , Fig. 3, of the drill-head. Fig. 6 is a horizontal section through xx , Fig. 4, of the drill-head. Fig. 7 is a horizontal section through zz , Fig. 4, of the drill- 65 head. Fig. 8 is a sectional view of the several plates of metal in which holes have been punched, but which are not coincident with one another, with a reamer in them preparatory to reaming them, so as to be co- 70 incident. Fig. 9 is a sectional view of the same plates of metal after the drill has passed through and made the rivet-holes coincident. Fig. 10 is a side elevation of another application of my invention to a reaming-machine, 75 which, instead of being secured to a bracket secured to a wall, is mounted upon a movable carriage and provided with means by which it may make a complete revolution, the crane-arm describing a circle instead of 80 a semicircle. It also has means for the elevation of the crane-arm vertically upon the post of the carriage. Fig. 11 is a front elevation of the device by means of which the vertical adjustment of the crane-arm is accom- 85 plished. Fig. 12 is a sectional view of the sleeve and means of attachments of the crane-arm and the elevating device. Fig. 13 is a rear elevation of the upper end of the sleeve to which the crane-arm is attached and which 90 fits over the pillar upon the carriage. Fig. 14 is a part of the front elevation of the carriage, showing the series of small wheels by which it moves up the track.

Referring now to Fig. 1, 1 is a bracket, 95 which may be bolted against a wall. It is provided with holes for bolts. 2 is a sleeve-bearing cast onto the upper end of this bracket, through which there is a central hole 3 and on the exterior of which there is a shoulder 100 or flange 4. The lower end of this flange is provided with a cone-shaped bearing 5.

- 6 is a socket-bearing or step-bearing for the lower end of the shaft. 7 is a set-screw, which passes up through the bottom of the socket or step bearing 6, and 5 8 is a lock-nut upon said set-screw for locking it in any desired position. 9 are bolt-holes by which the step-bearing may be bolted to the bracket 1. 10 is a keyway cut half in the bracket 1 and half in the back of the step-bearing 6, in which a key 11 is inserted. This keyway is planed so as to be in exactly the proper position in relation to the step-bearing, in order that the bearing may be properly located in 15 relation to the bracket. The bolt-holes 9 simply serve to hold the step-bearing against the bracket while the downward pressure of the bearing is maintained upon the key 11, resting in its keyway 10. 20 12 is a crane-arm, which is secured in the bearing 2 and 6 by means of a shaft, or rather two shafts, one projecting upward from the rear end of the crane-arm and the other downward. The lower one 13 forms the foot, which 25 rests in the step-bearing 6. The upper one 14 is journaled in the hole 3 of the sleeve-bearing 2. The rear end of the crane-arm between the interior ends of the shafts 13 and 14 is hollow. Through the center of the 30 shaft 14 is a hole, through which passes the shaft 15, on either end of which is secured a mitered gear 16 and 17. The mitered gear 17 meshes with the mitered gear 18, which is at right angles to it, and which is keyed to 35 the shaft 19. Said shaft 19 is journaled in the bearings 20 and 21, which are severally mounted upon opposite sides of a sleeve 22, which surrounds the sleeve-bearing 2 and rests upon the shoulder or flange 4 thereof. 40 The sleeve 22 is provided with a set-screw 23, by means of which it may be fixed at any desired point. Surrounding the shaft 14, upon the upper surface of the rear end of the crane-arm, is a conical socket, which is of the same 45 pitch as the cone-bearing 5, and which forms with said cone 5 a bearing. This cone-bearing is a friction device which will aid the set-screw 7 to fix the crane-arm at any desired radial position. Upon the rear end of the 50 shaft 19 is secured a cone-pulley 24, by which power may be applied to the shaft 19 and to the train of gears connected therewith. 25 is a shaft journaled at the two ends of the crane-arm, one end at 26 and the other 55 end at 27. Upon the end next the bracket of the shaft 25 is secured a mitered gear 28, which meshes with the mitered gear 16 and gets motion from it. The shaft 25 is provided with a feather 29, and is the means by 60 which a sleeve 77, sustained in a bearing upon a bracket on upper end of the drill-head casing is caused to revolve. On one end of this sleeve 77 is secured a beveled gear 35 and on the other end a cone-pulley 76. 65 The crane-arm 12 consists of two T-rails 30 and 30, which are secured together at both ends, but open in the center, so that the carriage of the drill-head and the drill-head may travel between them. 31 and 31 are steel bearing-rails secured 70 upon the upper inner corner of the crane-arm, and upon which run the wheels 33 33 of the carriage carrying the drill-head. 34 is the upwardly-projecting bracket or arm upon which the sleeve 77, just described, 75 is journaled. 35 is a beveled gear upon one end of said sleeve. 36 is a beveled gear meshing with said beveled gear 35, and which is secured to the upper end of a sleeve 37. 32 is the casing of the drill-head. 80 38 38 are two friction-wheels, which are provided for the purpose of holding the drill-head firmly to the track when at work and preventing tilting, while at the same time allowing free motion of the drill-head upon 85 the track. They also serve the purpose of clamping the drill-head upon the crane-arm at any desired point. There are two pair of the wheels 38 38, and one of each pair is journaled in the end of a yoke 39 39, which rest 90 upon the ends of the screws 40 40, each of which is threaded in holes through the center of one of the legs of a U-shaped lever 41. This lever 41 is pivoted at 42 and passed around three sides of the drill-head. The 95 loop of the U-shaped lever is provided with a bearing-screw 44, which passes through a lug 45, cast on the side of the drill-head casing, and 46 is a lock-nut by which the screw 44 may be maintained at any desired elevation. It will thus be seen that any desired pressure may be exerted upon the wheels 38 38 by simply turning the screw 44 and locking the nut 46. 100 Referring now to Fig. 4, 47 is the drill-shaft, 105 upon one end of which there is secured a drill-mandrel 50, above which there is a collar 51. 48 is a sleeve surrounding the shaft and separated from it by bush-bearings 49 49. 110 These bush-bearings are generally of brass or other bearing metal. The upper end of the drill-shaft is provided with a feather 52, which passes through a bearing, to which it is splined in the lower end of the sleeve 37, which is 115 connected to the gear 36, and by means of which rotary motion is given to the shaft. 53 and 54 are two lock-nuts screwed upon the shaft 47 about midway of its length, and when screwed tightly upon one another they 120 form a rigid collar upon said shaft. 55 is a collar surrounding said shaft, although not secured to it, except by a pin which passes through both collar and shaft and projects beyond the collar, the ends 56 56 of which 125 pin are provided with holes 57 57 vertically through them, Fig. 5, these ends 56 56 projecting beyond the walls of the case through slots 80 80 therein. 59 is a rack vertically secured to the side 130 of the sleeve 49, meshing with the pinion 60, which is keyed to the shaft 61. To one end

of the shaft 61 is keyed the hand-wheel 62 and to the opposite end a sleeve 63, which is squared. Upon the squared sleeve 63 is fitted a clutch-ring 64, which is provided with 5 square clutch-notches on the side next the drill-shaft 47.

65 is another sleeve upon the round part of the shaft 61, and is provided on the side next the clutch-ring 64 with indentations and elevations corresponding to those of the clutch-ring, so that the sleeve 65 and the clutch-ring may be thrown into engagement, and when so engaged the sleeve 65, with its worm-wheel 66, will turn the shaft 61.

15 Referring to Fig. 6, 67 is a screw or worm secured to the shaft 68. To one end of said shaft is secured the hand-wheel 69 and to the other end the gear 70.

71 is a lock-nut upon the end of shaft 68, 20 by which gear 70 is held in place. The worm 67 meshes with the worm-wheel 66 and gives motion to it when the shaft 68 is turned by the hand-wheel 69. The gear-wheel 70 meshes with a pinion 74, which is mounted upon a 25 shaft 73, hung upon a bracket-bearing 72, projecting from the outside of the casing 32. On the other end of the shaft 73 is keyed a set of cone-pulleys 75.

It will be observed by reference to Fig. 4 30 that this set of cone-pulleys is located in a vertical line immediately below the cone-pulleys 76, upon the sleeve 77, and which are turned by the main driving-shaft of the machine 25. It will thus be seen that power 35 may be applied to the cone-pulleys 75 and the feed of the machine accomplished by means of power.

It is very important when doing rapid work, in order to do it effectually, that the drill or 40 reamer may be withdrawn from its work rapidly. This is done by the following mechanism: The clutch 64 is thrown out of engagement with the worm-wheel 66, and by turning the hand-wheel 62 the pinion 60 may 45 be turned directly, thereby raising the sleeve 48 and pushing up the drill-shaft by means of the collar 55. This would be difficult and laborious were not the weight of the drill-shaft counterbalanced. This is done by 50 means of cords which are secured to the projecting ends 56 56, Fig. 5, of the pin, which passes through the shaft and ring 55, and which pass up on the outside of the casing of the drill-head and over the inclined pulleys 81.

55 These cords are marked 80 $\frac{1}{2}$ and pass down into a well 78 within the casing of the drill-head. Upon the ends of the cords 80 $\frac{1}{2}$ are secured counterbalance-weights 79 79. The counterbalance weight or weights move up 60 and down inside of this well and therefore entirely out of the way. One pulley may be employed to counterbalance the weight, but I prefer to employ two—one on either side of the drill-head, because by this means I can 65 get an equal distribution of weight on both sides of the drill-head. This is an important

feature, as the balance and ease of motion of my machine is one of its best features.

Figs. 10, 11, 12, and 13 show an application of my invention which is only slightly different from that heretofore described. The invention proper is the same. I have only applied it in a little different way, which is capable of a greater variety of motions. This application consists of mounting the crane-arm upon a carriage, through which it may be moved upon a track in a horizontal line or rotated in a complete circle, so as to operate upon two pieces of work in rapid succession.

80 Referring to Fig. 10, 83 83 is a track laid upon suitable foundation.

84 is a rack secured to the inside of one of the tracks.

85 is a carriage mounted upon the track 83 85 and resting upon a series of small rollers 87 87, which may be of any suitable number to prevent friction.

86 86 are projecting plates secured to the under side of the carriage on either side and 90 projecting beneath the outer flange of the top of the rail. These plates 86 86 hold the carriage upon the track and prevent its being raised off by the weight of the crane-arm.

88 is a shaft, which is journaled in the base 95 of the carriage, on one end of which there is a hand-wheel 89 and upon the other a pinion 90, which meshes with the rack 84, and by which the carriage and the whole drilling apparatus may be moved upon the track.

100 91 is a pillar mounted upon the carriage 85.

92 is a sleeve fitting on the pillar and covering it from one end to the other. The pillar 91 is conical in form and so is the sleeve 92. The sleeve 92 is split down the center 105 on one side.

93 93 are projecting lugs on either side of the slit, and 94 94 are bolts passed through the holes in the lugs 93 93 and employed to tighten the sleeve upon the pillar, so as to 110 create any desired amount of friction between it and the pillar.

95 95 are laterally-projecting vertical flanges extending from the surface of the sleeve 92, and which have upon their ends laterally-projecting gibs or flanges 96, which serve as guides for the rear end of the crane-arm.

97 is the bracket of the crane-arm. It is in this figure marked 97, although it occupies the same relative position and serves the same 120 purposes as the plate 1 in Fig. 1. Upon the interior of the plate 97 there is a channel-way 98 planed out, into which fits the laterally-projecting gibs or guides 96 96. Upon the rear side of the plate 97 are bolted two plates 125 99 99, which project inwardly over the laterally-extending flanges 96, and form a binding-plate by which the bracket 97 is secured to the guides 96 96.

130 100 is a block or nut secured to the inside of the bracket 97, and through which passes the screw 101. This screw 101 is secured at

- both ends between the guides 96 96 to cross-frames provided for the purpose. The upper end is secured to 103 and the lower one to 102, as shown in Fig. 11.
- 5 104 is a beveled gear secured to the lower end of the screw 101.
- 105 is a similar beveled gear meshing with gear 104 and secured to a shaft 106 at right angles to the screw.
- 10 107 is a crank connected to the shaft 106 and by which the mitered gears 104 and 105 and the screw are turned.
- 15 108 108 are the sheaves over which the cords pass, by which the crane-arm is counterbalanced.
- 109 is the cord, and 110 are the counterbalance-weights. They are in this case, entirely outside of any casing and not, as in the device shown in former figures, in a pocket.
- 20 111 is the shaft by which the beveled gear marked 16 in Fig. 1 is turned. This shaft, instead of being short and having a beveled gear at the upper end, is a long shaft provided with a feather 112. It passes through 25 a sleeve and gear 114, which are journaled in a bracket 113, secured to the upper end of the sleeve 92. The gear 114 meshes with a gear 115, which is mounted upon a stud upon the upper surface of the bracket 113.
- 25 116 is another gear, which meshes with 115, and is secured to the bottom of a sleeve 117, to the top of which is secured the beveled gear 118, which meshes with another beveled gear 120, secured to a shaft 123. The sleeve 30 117 is mounted upon a pin-shaft 119, which is inserted in the top of the pillar 91.
- 121 is a sleeve surrounding the sleeve 117, and to which are secured the upwardly-extending arms 122 122, on the upper ends of 40 which are bearings for the shaft 123, which is journaled in them, and which is provided on one side of said bearings with the beveled gear 120 and on the other side with the cone-pulley 124.
- 45 This device will allow the sleeve 121, carrying the driving mechanism, to rotate upon the sleeve 117 and be placed parallel to a driven counter-shaft, wherever such may be.
- 50 What I desire to secure by Letters Patent, and what I claim as new is—
1. The combination of a crane-arm suitably mounted upon devices for sustaining the same, said crane-arm consisting of two parallel tracks, a driving-shaft suitably journaled parallel with said track, a carriage mounted and moving upon said track, and a drill-head borne by said carriage, consisting of a drill-shaft geared to the driving-shaft by gearing which will slide upon it, the whole drill-head being centrally located between the tracks, substantially as described. 55
  2. The combination of a crane-arm suitably mounted upon devices for sustaining the same, said crane-arm consisting of two parallel tracks, a driving-shaft suitably journaled parallel with said track, a carriage mounted
- and moving upon said track, and a drill-head borne by said carriage, consisting of a drill-shaft geared to the driving-shaft by gearing which will slide upon it, and a set of retaining-wheels for the carriage, journaled in a lever secured to the drill-head and bearing upon the under side of the track, and clamping devices for clamping the retaining-wheels upon the track, the drill-head being centrally located between the tracks, substantially as described. 70
3. The combination of a crane-arm suitably mounted upon devices for sustaining the same, said crane-arm consisting of two parallel tracks, a driving-shaft suitably journaled parallel to said tracks, a carriage mounted and movable upon said tracks, and a drill-head borne by said carriage, consisting of a drill-shaft geared to the driving-shaft by gearing which will slide upon it, and a set of retaining-wheels journaled in a lever secured to the drill-head and bearing upon the under side of the track, and a drill-shaft geared to the driving-shaft by gearing which will slide upon it, the whole drill-head being centrally located between the tracks of the crane-arm, substantially as described. 75
4. The combination of a crane-arm suitably mounted upon devices for sustaining the same, said crane-arm consisting of two parallel tracks, a driving-shaft suitably journaled parallel to said tracks, a carriage mounted and moving upon said tracks, and a drill-head borne by said carriage, consisting of a drill-shaft geared to the driving-shaft by gearing which will slide upon it, and being splined to the gear to permit vertical motion, the whole drill-head being centrally located between the tracks, and counterbalance devices for counterbalancing the weight of the drill, substantially as described. 80
5. The combination of a crane-arm suitably journaled to a wall-bracket, said crane-arm consisting of two tracks upon which is mounted a drill-head, said drill-head being secured to a carriage which runs upon said track and being located between the tracks, and a driving-shaft journaled upon the crane-arm and parallel to it, the drill-shaft being at 85 right angles to the driving-shaft and geared to it by gearing which will slide upon the main driving-shaft, and a collar secured upon the drill-shaft about midway of its length and provided with lugs on either side, to each of which is secured a cord which passes over a pulley on either side of the drill-head, at the other end of which is secured a counterbalance-weight, said driving-shaft being secured to its gearing by a feather or other equivalent device in such manner that it may rise and fall with freedom under the influence of the counterbalance-weight, substantially as described. 90
6. In a drilling or reaming machine, the combination of a carriage mounted upon a suitable track, upon which there is a verti- 95

cal post, with a sleeve fitted to said post and arranged to revolve upon it, a crane-arm secured to the side of said sleeve by a sliding connection, and means for raising and lowering the level of the crane-arm, counterbalance devices for counterbalancing the weights of said crane-arm mounted upon the sleeve, and an anti-friction drill-head mounted upon a

suitable carriage and running upon the crane-arm, and devices for operating the drill in the drill-head, substantially as described.

WILLIAM BISHOP HUGHES.
